DESIGN FOR PAJAMAS OR SIMILAR ARTICLE

Ethel Eaton Stricker, New York, N. Y.

Application August 27, 1936, Serial No. 64,583

Term of patent 3½ years

To all whom it may concern:

Be it known that I, Ethel Eaton Stricker, a citizen of the United States of America, residing in Manhattan, county of New York and State of New York, have invented a new, original, and ornamental Design for Pajamas, or Similar Article, of which the following is a specification, reference being had to the accompanying drawing, forming part thereof, wherein,

I claim:

The ornamental design for pajamas, or similar article, substantially as shown.

ETHEL EATON STRICKER.
